(57) **CLAIM**

The ornamental design for an intramedullary fastener, as shown and described.

DESCRIPTION

FIG. 1 is a front perspective view of an intramedullary fastener showing the new design;
FIG. 2 is a back perspective view of the design of FIG. 1;
FIG. 3 is a sectional view the design of FIG. 1 taken along line 3-3 of FIG. 1;
FIG. 4 is a sectional view the design of FIG. 1 taken along line 4-4 of FIG. 2;
FIG. 5 is a top view of the design of FIG. 1;
FIG. 6 is a bottom view of the design of FIG. 1;
FIG. 7 is a left elevational view of the design of FIG. 1;
FIG. 8 is a right elevational view of the design of FIG. 1;
FIG. 9 is a front elevational view the design of FIG. 1; and,
FIG. 10 is a back elevational view the design of FIG. 1.
The broken lines shown in FIGS. 1-8 illustrate portions of the intramedullary fastener that form no part of the claimed design.

1 Claim, 5 Drawing Sheets

Related U.S. Application Data

a continuation-in-part of application No. 14/776,418, filed on Sep. 14, 2015, now Pat. No. 9,907,562.
